ABSTRACT

Apparatus for controlling the operation of a knitting machine in response to the tension of the yarn comprising a crank member having a yarn guide fixed thereto, and being resiliently biased in one direction, the crank being reversible in response to a predetermined tension to operate control means for stopping the machine.

6 Claims, 5 Drawing Figures

STOP MOTION CONTROL DEVICE FOR KNITTING MACHINES

The present invention relates to apparatus for feeding yarn to a knitting machine and in particular to apparatus for controlling the operation of said machine in dependence upon the tension on said yarn.

As is well known yarn is fed to the thread guides in an automatic knitting machine from individual spools mounted on a frame or creel. To insure proper and continued operation of the machine it is provided with one or more control devices responsive to yarn tension and continuity. One such device comprises a stationary arm carrying a forked yarn guide and a pair of movable arms one of which is adjustably rotatable while the other is a freely pivoted counterweighted arm. The rotatable and counterweighted arms are secured to independent shafts mounted within a carrying sleeve adapted to have fixed thereto the stationary guide arm. The rotatable arm is spring mounted and is adjustable to provide a fixed tension on the yarn as the yarn is fed to the stationary arm while the pivoted counterweighted arm is freely movable in response to the tension of the yarn. Yarn is passed over each of the rotatable and pivotal arms serially as it is fed to the stationary arm from whence it is fed to the thread guides. The rotatable arm and the pivoted counterweighted arm and the carrying sleeve within which the shafts are mounted are provided with cooperating electrical contact members. The electrical contact members are connected to various machine control elements in a manner whereby movement of the pivoted counterweighted arm, either as a result of excessive or insufficient tension, or movement of the rotatable arm, as a result of yarn breakage, causes the knitting machine to stop operation. Thus it will be observed that the knitting machine can be controlled in its operation in response to the yarn tension and yarn continuity.

In general all known yarn tension and yarn continuity devices operate in the same manner by detecting independently the tension of the yarn and the yarn continuity. The major disadvantage of these devices consists in that the conventional apparatus is very sensitive to even minor changes in yarn tension which as is well known may occur from improper formation of the yarn diameter, or the winding of the yarn upon the bobbins as well as a number of other factors none of which are by themselves sufficiently serious to warrant the stopping of the machine. Consequently the knitting machine is often stopped for no apparent reason. It will be appreciated that the stoppage of the knitting machine requires that the operator determine the cause of the stoppage, inspect the work product as well as the yarn and then restart the machine. This operation is particularly troublesome when there is in fact no good reason for the machine to have been stopped in the first place. In an effort to overcome this inconvenience, the tension guide is often set at a limit which is beyond the tensile strength of the yarn. Consequently the yarn breaks before the machine is stopped. This state of affairs is even more serious than the prior described disadvantage.

It is an object of the present invention to provide a mechanism by which the disadvantages inherent in the prior art devices can be overcome.

It is a particular object of the present invention to provide a mechanism for controlling the knitting machine operation in response to the tension of the yarn fed there through operable only upon the tension reaching a predetermined limit.

It is a further object of the present invention to provide a control device for operating knitting machines which is adjustable and which may be preset to specific yarn tension limits.

It is still another object to provide a tension control device to avoid yarn breakage.

According to the present invention there is provided in association with conventional knitting machine control means, a pivoted yarn guide fixed to a unidirectional spring loaded over-the-center crank. The crank is adjustably loaded so as to have a predetermined resiliency to the tension of the moving

yarn and to be responsive instantly to excessive tension of the yarn as it passes over the guide. The crank being thereafter adapted to close contacts with the machine control means whereby operation of the machine may be stopped.

The aforementioned objects and advantages as well as numerous others will be seen from the following description wherein reference is made to the appended drawings, in which:

FIG. 1 is a front elevation of a longitudinal section through the device of the present invention in operation;

FIG. 2 is a side elevation of the longitudinal section of FIG. 1 taken along the lines A A of FIG. 1;

FIG. 3 is a view similar to FIG. 1 showing the device of the present invention operative in response to an excessively tensioned yarn;

FIG. 4 is an enlarged view of the electric contact portion of the present device;

FIG. 5 is a diagram of the electric circuit of the present device.

Before turning to the specific description of the present invention it is necessary to note that the description herein is limited to the device for determining excessive tension of a yarn thread. The structure of the knitting machine as a whole and the showing of yarn bobbins, creels, feed mechanisms, thread guides etc. is omitted from the present description. It is felt that a description of this related material is unnecessary since they are well known in the prior art and to those skilled in the art and for the sake of brevity the present description describes only those elements which are absolutely necessary for the understanding of the present invention.

Turning to FIGS. 1 through 3 the present device comprises a rectangular box like body 1 having a hollow cavity 3 at its upper end, and a cover 2 which may be secured thereto in any conventional manner.

The body 1 is preferably formed of non-conductive material while the cover 2 is preferably formed of conductive or metallic material for reasons to be explained later. Secured within the back wall of the body 1 and the cover 2 (as seen in FIG. 2) are coaxially opposed friction bearing

members 4 and 5, respectively. The bearing member 4 may be made of nylon or other similar plastic material which is non-conductive while the bearing 5 is made of conductive material. Both bearing 4 and 5 are force fit within recesses formed within the body and cover, respectively. Located within the body cavity 3 is a crank member 8 having extending wing like arms 6 and 7 rotatably secured within the bearing members 4 and 5, respectively. The crank member 8 is bifurcated in its central section to provide a forked shaped recess 9 through

which is transversely mounted a wrist pin 10. The wing like arm 7 extending through the lid 2 is elongated and is provided with a transverse hole in which is inserted a normally horizontally extending arm 11 of a yarn hook 12. The arm 12 is maintained in fixed position within the elongated crank arm 7 by a conventional screw member and the yarn hook 12 is smoothly formed and it is adapted to hold the yarn as the yarn is fed to the knitting machine.

A rod 14 is freely secured to the wrist pin 10. The rod 14 is likewise freely secured at its other end to a second wrist pin 15 which is transversely secured within the end of a piston member 16 mounted so as to be freely movable in a bore 40 formed within the lower solid portion of the body member 1.

The piston 16 is provided with an axial recess 17 within which one end of a tension spring 18 is fixed. The bore 40 is threaded at its outer end and is provided with a correspondingly threaded knob 19 the face of which abuts against the lower end of the spring 18 thereby resiliently loading the piston 16. The loading of the piston 16 (that is the action of the spring 18 on the piston 16) may be adjusted by turning the knob 19.

It is to be noted from FIG. 1 that the device is arranged so that within predetermined limits of tension on the yarn 13 the arm 11 will extend horizontally from the body 1 and permit the thread 13 to be guided endlessly over the hook 12. In this position the crank 8 and extending rod 14 are angularly disposed to each other about the wrist pin 10 and resiliently

biased in one direction to abut against one of the interior walls of the cavity 3. On the wall opposite the normal abutment of the crank 8 and 14 there is located a pair of electrical terminal contacts 20 and 21. Contact 21 is provided with a resilient leaf spring 21a which extends over the contact 20 and is normally out of electrical contact therewith. Extending from contacts 20 and 21 are electrical leads 22 and 23, respectively. As will be noted from FIG. 3 should the yarn guide hook 12 and the arm 11 be depressed, as for example by excessive tension on the thread 13 the crank 8 and extension 14 pivot in the direction of arrow S (FIG. 1) and reverse their positions to abut against the opposite wall of the cavity 3 and in contact with the contacts 20 and 21. In doing so the crank 8 and extension 14 force the leaf spring contact 21a into electrical connection with the contact 20 thus completing the circuit between these two contacts. Of course adjustment of the knob 19 will determine the limit of tension tolerated by the device.

Turning also to FIG. 5 it will be noted that the lead 22 from the contact 20 is grounded which may as for example be by connecting the same to the knitting machine (not shown) itself. The lead 23 from the contact 21 on the other hand is connected to one terminal of a transformer 24 through a series connection with a lamp 25. The transformer 24 may be a separate device connected to an alternating current line source, for example, or it may be the power source for the entire knitting machine if desired. The second outlet terminal of the transformer 24 is also grounded as for example to the knitting machine.

The first terminal of the transformer 24 is connected, in addition to the lamp 25, to a pair of switches 26 and 27, across which are connected a resistor 29 and the terminal C of a multiple terminal solenoid relay 28. The coil 30 of the solenoid relay 28 is connected at one end to the ground and at the other end between the resistor 29 and the cover 2. As can now be seen the cover 2 acts as a separate and distinct ground or common contact, labeled X in the drawings to which one or more of the circuit components may be connected. It is for this reason that cover 2 should be metallic or otherwise conductive. It will be appreciated that the body 1 may be conductive while the cover 2 nonconductive if desired. The remaining terminals A and B of the relay 28 are connected to various power line sources for motors etc. of the knitting machine itself, so that upon actuation of the coil 30 the knitting machine may be stopped or started as desired.

The device just described functions mechanically in the following manner: A yarn 13 is withdrawn from a selected bobbin located on a creel (both of which are not shown) and suspended over the hook 12 which is horizontally disposed in its normal operating position. The yarn 13 as it moves, being pulled from the bobbin by operation of the knitting machine, exerts a force upon the hook 12 pivoting the arm 11 and the crank 8 in the direction of arrow S (FIG. 1). The rate of turning of resiliently biased crank 8 is of course controlled by operation of the spring loaded piston 16 which as noted previously has been preset to a predetermined tension level by adjustment of knob 19. The preadjustment of the spring 18 provides a maximum force which can be exerted by the yarn 13 in the direction S upon the guiding arm 11. This maximum force is determined differently for each knitting machine, the yarn being processed and other similar well known operating factors. So long as the yarn 13 does not exert a force greater than the maximum force or tension of the spring 18 the yarn continues to be guided over the hook 12 which remains in a substantially horizontal position, the crank 8 and piston rod 14 moving between a dead center position and its normal operating position as shown in FIG. 1. Should, however, the force on the yarn exceed the maximum predetermined limit set by the spring 18 as seen by yarn 13 in FIG. 3, then the crank 8 and rod 14 move beyond the dead center position and instantaneously reverse their angular disposition within the cavity 3. Thereupon the crank 8 abuts against the contact 12a and completes the contact between the electrical terminals 20 and 21. In the course of the motion of the crank 8 from its normal

operating position to its reverse position as shown in FIG. 3 the arm 11, at which end the hook 12 is provided, pivots downwardly from a substantially horizontal position to acute angular position allowing the yarn to fall from the hook 12. This pivoting the arm 11, which permits the yarn to fall, prevents the breakage of the yarn due to any increased tension on the yarn itself.

Turning to FIG. 5 the electrical operation of the device is seen. Initially the control device is set by closing both switches 26 and 27 thereby completing circuit between the transformer 24, the resistor 29 and the coil 30 of the relay 28. On activation of the coil 30 the relay contacts 28 shift (to the right as seen in the FIG. 5) so that contact is made from the transformer 24 through switch 26 through contact C of the relay 28 thence through the resistor 29 and into the coil 30 thereby holding the coil 30 in its inward or right hand position. Simultaneously the switch 27 may be released and left open, the solenoid relay 28 being fixed in contact position. In contact position relay contacts A AND B are operative to permit the knitting machine to operate. So long as the yarn 13 does not exceed its predetermined maximum tension, the circuit just described remains stable. However at the moment in which the crank 8 mechanically reverses its position and closes the contacts 20 and 21 the circuit governing the activation of the coil 30 is shorted from the resistor 29 to the cover 2 and its common conductive portion "X" completing a circuit through the switch members 20 and 21, lead 23, lamp 25 and the transformer 24. As this occurs the coil 30 is deactivated and automatically reverses its position causing all the relay contacts A, B and C to break. As contacts A and B break, the knitting machine is caused to instantaneously stop. Simultaneously with the stopping of the knitting machine the lamp 25 becomes illuminated indicating to the operator the fact that machine has stopped.

The knitting machine will remain stopped and will not automatically return to active position until the operator manually replaces the hook member 12 and arm 11 to its upward horizontal position to thereby release the crank 8 from the contacts 20 and 21. It will be noted from FIG. 3 that the crank 8 is constantly held in its reverse position due to the tension placed upon it by the spring 18. Therefore the manual reversal of the hook and arm members 11 and 12 provides an advantageous safety feature in that the machine cannot be inadvertently restarted, without fixing the yarn. The reversal of the crank member 8 does not, however, automatically rest the electrical components of the knitting machine which must also be manually accomplished by the operator. This is done, by again depressing the switch 27 and closing the circuit between it and the relay coil 30 as described earlier. The relay coil 30 on reactivation again shifts contacts 28 so that the circuit between contacts A, B and C with the motors of the knitting machine and the resistor 29, respectively, can be completed.

It will now be seen that the present invention provides a simple but effective and novel device for controlling the operation of a knitting machine in response to yarn tension. It will be observed that momentary fluctuations in yarn tensions do not effect a stoppage of the knitting machine, nor does excessive tension result in yarn breakage. The device is highly adjustable and clearly operative in many applications and with a variety of knitting machines and yarn. Any number of modifications and changes will be readily apparent to those skilled in the art and it is therefore intended that the present disclosure be taken solely as illustrative of the inventive concepts.

What we claim:

1. Apparatus for controlling the operation of a knitting machine in response to the tension of a yarn fed thereto comprising a hollow walled body, switch means mounted on one wall of said body, a unidirectional over-the-center crank member having a pair of opposed axial extending arms pivotally secured within said body to pivot about a fixed axis, said crank member being pivotable about the axis of said arms between a first position in engagement with said switch and a second position out of engagement with said switch, a piston

located within an axial bore in a wall of said body offset from said one wall and transverse to the pivot axis of said crank member, a rod pivotally connected at its ends to said crank member and said piston respectively, cooperating therewith to form an articulated connection between said crank member and said piston, a spring fixed to said piston within said bore to apply a predetermined force to said piston to normally bias said crank member in said second position, a yarn guide fixed to said crank member and extending outwardly of said body to receive a moving yarn, said guide being adapted to pivot said crank member in response to the tension on said yarn and to overcome the biasing of the crank member by said spring and piston, said crank member being moved to said first position in response to a predetermined level of tension exceeding the predetermined force of said spring and means operative upon engagement of said crank member with said switch to effect the stoppage of said knitting machine.

2. The apparatus according to claim 1 including a knob threaded in the piston bore adapted to turning to selectively

adjust the strength of the spring to thereby vary the biasing of the crank member.

3. The apparatus according to claim 2, wherein the switch includes a normally open electric contact operably closed by the crank member on reversal thereof.

4. The apparatus according to claim 1 wherein the means operable to effect stoppage of the machine includes a self holding relay disconnected on operation of said electric contact, said relay having contacts forming a portion of the electric circuit of the knitting machine.

5. The apparatus according to claim 4 including means for preventing resetting of said relay until return of the crank member to its normally biased position.

6. The apparatus according to claim 5 wherein the body is formed of at least two parts only one of which is conductive, which conductive part forms a portion of the electric circuit, at least one arm of the crank member being secured within said nonconductive part.
